(57) **CLAIM**

The ornamental design for a powered staple gun, as shown and described.

DESCRIPTION

FIG. 1 is a perspective view of a powered staple gun of the present invention.

FIG. 2 is a front view of the powered staple gun according to FIG. 1.

FIG. 3 is a rear side view of the powered staple gun according to FIG. 1.

FIG. 4 is a right side view of the powered staple gun according to FIG. 1.

FIG. 5 is a left side view of the powered staple gun according to FIG. 1.

FIG. 6 is a top view of the powered staple gun according to FIG. 1; and,

FIG. 7 is a bottom view of the powered staple gun according to FIG. 1.
